(57) **CLAIM**

The ornamental design for a tilted plate, as shown and described.

DESCRIPTION

FIG. 1 is a perspective view of the present invention; FIG. 2 is a perspective view of the tilted dinner plate shown in an environment of use;

FIG. 3 is a cross-section view taken along line 3-3 of FIG. 1;

FIG. 4 is a cross-sectional view taken along line 4-4 of FIG. 2;

FIG. 5 is a bottom view of FIG. 1; and,

FIG. 6 is a partial bottom view of FIG. 1, with the broken lines illustrating the point at which the view was broken away from the FIG. 1 and forming no part of the claim.

The broken lines are included for the purpose of illustrating environment and form no part of the claimed design.

1 Claim, 3 Drawing Sheets

FIG. 3

FIG. 4

FIG. 5

FIG. 6
